UNITED STATES PATENT OFFICE.

SOLOMON D. WENETSKY, OF DORCHESTER, MASSACHUSETTS.

SLIDING CASTER.

Application filed January 21, 1927. Serial No. 162,862.

This invention relates to that class of sliding casters or glides for the legs of furniture which comprise a sheet metal dome shaped device, from the rim or circular edge of which three or more integrally formed prongs project, said prongs being adapted to be driven into the leg, to hold the device in position and to provide a smooth surface for the end of the leg to which it is attached. 10 One of the chief difficulties which have been encountered in the use of these devices is in the secure attachment thereof to the furniture leg, on account of the danger of splitting the wood, when the attaching 15 prongs are driven therein. The tendency of the prongs to split the wood depends on several factors, one of the most important of which, aside from size, is the distance from the point where the prong enters the 20 wood to the adjacent side of the leg.

It is desirable to have the external diameter of the dome portion of the caster, at the point where it engages the wood, as great as possible in comparison to the width or diameter of the leg to which it is to be attached, but, where the outer sides of the prongs are flush with the outer edge of the rim of the dome, it is necessary, to avoid splitting, to employ a caster having a diameter which is 25 substantially less than the diameter or thickness of the leg.

To enable the use of a caster which approximates more nearly in diameter to the diameter or thickness of the leg, sliding 30 casters of this type have been produced in which the prongs were set in from the rim, this having been accomplished by indenting the dome part at the points where the prongs are connected thereto so as to set the prongs 35 inward, also by slitting the rim of the dome in line with the side edges of the prongs and then bending the latter inward at the point of connection and folding the adjacent portions of the rim against the outer sides of 40 the prongs. These constructions are, however, objectionable partly from the stand-point of appearance, as the exterior of the dome is cut or indented, but largely for the reason that the indentations or sharp projections which are formed to set in the 45 prongs, are liable to catch in the tufting of carpets or rugs, on which the casters are 50 likely to be slid.

The objects of my invention are to provide 55 a form of sliding caster of the type above referred to in which the prongs shall be set

in from the edge of the dome portion to a substantially greater extent than what has previously been considered practicable, and at the same time, to produce a dome portion 60 which is perfectly circular and is without slit or indentation therein and which is of substantially greater strength than similar devices of this character, so that it will have greatly increased rigidity at its rim and is 65 unlikely to be distorted either by the act of driving the prongs into the wood or to be flattened or indented by subsequent use.

Also to provide a device having the above 70 described characteristics which may be formed from sheet steel by a stamping or dieing operation.

I accomplish these objects in the manner hereinafter described and as illustrated in the accompanying drawings, in which:— 75

Fig. 1 is a bottom plan view, Fig. 2 a side elevation and Fig. 4 a top plan view of a preferred embodiment of the invention.

Fig. 3 is a central sectional view at line 3—3 of Fig. 1. 80

Figs. 5 and 6 are plan and edge views of the original blank and

Figs. 7 and 8 are sectional views indicating steps in the forming operation.

As shown in the drawing the caster comprises a sheet metal piece shaped in dished form to provide a dome portion *a* having a base or rim portion *b*, on which a flat face *c* is formed and arranged to bear against the surface of the wood to which the device is attached, said rim portion being thickened or up-set at its edge to at least double the normal thickness of the material of which the caster is formed, and tapering in thickness to the middle portion of the dome, 95 which is of normal thickness.

A series of prongs *d*, preferably three in number are formed integrally with the rim and project perpendicularly from said face in circular relation, with the inner sides 100 thereof flush with the internal recess *e* formed in the inner side of the dome, the thickness of said prongs being the same as the normal thickness of the material, so that the outer sides of the prongs are at a distance from the outer periphery of the rim, or of face *c*, fully equal the thickness of the metal, whereby they are set in from outer surface of the dome to this extent.

In the formation of the caster, a blank 110 of the shape indicated in Figs. 5 and 6, is cut from somewhat malleable sheet metal,

and, by the same, or a subsequent operation, the blank is drawn into the elongated dome form shown in Fig. 7, in which the sides of the dome portion are cylindrical, while the 5 prongs are similarly shaped and form continuations of the cylindrical side portions. The shape and relative arrangement of the prongs is not changed by subsequent forming operations. By means of a swaging or 10 up-setting operation the elongated dome portion is then reshaped, so that the rim portion is spread out, this operation being performed by means of three dies, one of which fits against the inner sides of the prongs and 15 forms at its end to final shape of the cavity in the inner side of the dome, the second of which bears against the outer sides of the prongs and conforms to the face *c* of the dome rim and the third of which conforms 20 to the top surface of the dome, as indicated in Fig. 8.

With the above described construction, while the weight of metal required for its formation is slightly greater than that which 25 would be required for a caster of equal diameter of the common type in which the prongs are flush with the outer edge of the rim, yet the increased amount of metal is advantageously employed to increase, very 30 substantially, the strength of the rim, so that the dome part cannot be distorted or the prongs readily bent out of position by the driving in operation when attached.

Other important advantages are that a 35 caster of substantially increased diameter may be employed for a furniture leg of a certain size without danger of causing splitting, as compared with glides of the common type, and, at the same time, a caster 40 is produced in which all the exterior surface thereof, which is exposed when attached, is entirely free from projections and indentations. Also, for a caster of a certain diameter, as compared with the type having 45 prongs flush with the rim or outer periphery, the attaching prongs may be made longer and stronger without increasing the danger of splitting the wood when the caster is attached, and, at the same time, the danger 50 of bending the prongs, when they are driven into the wood, is reduced.

While the device could be made by a casting operation, it is highly advantageous to be able to make it by a dieing operation, as 55 this enables it to be manufactured by automatic machinery and makes possible quantity production at a low cost.

I claim:

1. A sliding caster for wooden furniture legs comprising a hollow dome having its 60 edge-portion up-set to form a thickened rim portion provided with a base face of greater width than the thickness of the material at the middle portion of the dome, and a series of attaching prongs integrally 65 formed with the dome and projecting from said face at a substantial distance within the outer periphery thereof.

2. A sliding caster for wooden furniture legs comprising a sheet metal dome having 70 its edge portion up-set to form a relatively thickened edge portion having a circular face arranged for engagement at its outer periphery with the surface of the wood to which it is attached, and a series of circularly 75 arranged prongs formed integrally with the dome and projecting from said face at a substantial distance within said outer periphery.

3. A sliding caster for wooden furniture 80 legs comprising a sheet metal piece shaped in dished form to provide a middle bearing portion of approximately the normal thickness of the material and having a smooth exterior and a continuous rim portion up-set 85 to form a base face of a width approximately double the thickness of said bearing portion and tapering in thickness to said bearing portion, and a series of circularly 90 arranged prongs of the normal thickness of the material and extending continuously therewith from said face with their inner sides cylindrically arranged and continuous 95 with the inner periphery of said face and with their outer sides at a substantial distance within the outer periphery of said face.

4. A sliding caster for wooden furniture legs comprising a sheet metal dome having 100 its edge portions up-set to form a thickened rim portion having a base face at its edge for engagement with the material to which it is attached, said edge portion tapering in thickness from said face to the normal thickness of the material at the middle portion of the dome and a series of attaching prongs formed integrally with the dome and projecting perpendicularly from said face at a substantial distance within the outer periphery thereof.

In testimony whereof, I have signed my name to this specification.

SOLOMON D. WENETSKY.
